UNITED STATES PATENT OFFICE.

JOHN M. FARRA, OF LANCASTER, KENTUCKY.

RAIL TIE AND FASTENER.

No. 899,390.

Specification of Letters Patent. Patented Sept. 22, 1908.

Application filed February 26, 1908. Serial No. 417,888.

To all whom it may concern:

Be it known that I, JOHN M. FARRA, a citizen of the United States, residing at Lancaster, in the county of Garrard and State of Kentucky, have invented new and useful Improvements in Rail Ties and Fasteners, of which the following is a specification.

This invention relates to improvements in rail ties and fasteners, and contemplates the provision of a metallic tie having means for effectively clamping the rails and for retaining supports for the rails adapted to permit the rails to yield to a limited but desirable extent in the passage of the rolling stock thereover.

A further object of the invention is the provision of a simple, strong, durable and inexpensive construction of tie having supports and attaching means for the rails so disposed as to hold the rails in proper position and preventing them from spreading or from becoming depressed or otherwise shifted out of position by the strain of the car wheels and other conditions, and further to provide a construction which will permit of the ready application and removal of the rails.

The invention consists of the features of construction, combination and arrangement of parts hereinafter fully described and claimed, reference being had to the accompanying drawing, in which:

Figure 1 is a perspective view of one-half of a railway tie embodying my invention. Fig. 2 is a side elevation of the same, showing a rail supported and clamped in position, such rail appearing in transverse section. Fig. 3 is a top plan view of the parts shown in Fig. 2. Fig. 4 is a perspective view of the inner rail clamp.

In carrying my invention into practice, I provide a cast metal tie comprising a horizontal bed or base plate 1, from the center of which rises a vertical web 2, the intermediate portion 3 of which is reduced in height to secure lightness of weight, as well as to provide for the arrangement and reception between the ends of the tie of the water containing boxes or troughs employed for the supply of water to traveling locomotives.

The web 2 is stayed and connected on opposite sides with the base plate 1 by angular braces 4, which may be arranged at any desired intervals apart, and at each end the web is divided to form spaced clamp supporting portions 5 and 6 which extend upward to a greater height than the intermediate por-

tion 3. A box or compartment 7 is formed between these supporting portions 5 and 6 by spaced transverse plates 8 which are integral with the base plate and web section and extend to a uniform degree laterally from opposite sides of the web sections the full width of the rail, the laterally extending ends of the plates being connected by cross pieces 9 forming the ends of the box as well as strengthening members. The base plate 1 is of uniform thickness throughout, except as to that portion forming the bottom of the box or compartment, which is of increased thickness to provide additional strength at a point receiving the weight and strain of the rails in the passage of rolling stock thereover. The said box or compartment is adapted to receive a seat block 10 which forms the direct support for the rail 11. In practice, this block may be creosoted, or otherwise treated to increase its durability and capacity to withstand climatic changes, and it will be understood that the purpose of employing such blocks is to utilize the slight expansion and contraction permitted by the particular material of which they are composed to permit the rail to yield vertically to a limited but desirable extent upon the passage of the wheels of a car thereover, so that a portion of the weight and strain will be absorbed and excessive vibration of the rolling stock prevented.

The upper edges of the clamp supporting portions 5 and 6 of the web are each formed with a transverse head 12 formed by opposite laterally extending flanges 13, and at the outer end of the head of the supporting portion 6 is formed a transverse shoulder 14.

The upper faces of the heads 12 are plain surfaced to form seats for a pair of rail clamps 15 and 16, while the under faces of the flanges 13 are beveled inwardly and downwardly similar to the corresponding flanges of an ordinary T-beam. The clamps 15 and 16 are in the form of blocks having reduced inner ends 17 to bear upon the base flanges and opposite sides of the web of the rail 11 to firmly hold said rail in engagement with the block 10, and said blocks are provided with longitudinal slots 18 formed by downwardly and inwardly extending flanges adapted to receive and engage the lateral flanges 13, by which the blocks are adapted to be slidably mounted upon the supporting heads 12 for application and removal and adjustment to clamping position. The outer

clamping block 16, in the application of the clamps, is first applied to its head 12, after which the block 15 is applied and adjusted part way outward, the rail inserted, and the block 15 finally adjusted to clamping position, in which it is secured. It will be noted that it is necessary only to secure the block 15, as the block 16 bears against and is limited in outward movement by the shoulder 14.

10 In order to secure the block 15 in adjusted position, such block is provided upon one side and at its outer end with a depending lug 19 formed with an opening 20 for the passage of a retaining bolt 21 extending parallel 15 with the vertical web. This bolt is secured at one end by a bracket 22 to the part 5 and extends inwardly therefrom and is adapted to receive a clamping nut 23 which bears against the lug 19 to hold the block 15 from 20 inward movement. The same type of fastening devices may be provided upon opposite sides of the tie and block 15, for securing the block on each side of the tie, but the use of a double set of fastening devices under ordinary conditions is not essential.

From the foregoing description, taken in connection with the accompanying drawing, the construction and mode of operation of my improved tie and fastener will be readily 30 understood, and it will be seen that the invention provides a simple form of tie which may be economically manufactured and which possesses strength and durability, as well as a fastening means for the rails by 35 which the rails will be firmly held in position and yet permitted to have a slight vertical yielding motion. Hence, the rails will be held always at the proper distance apart, prevented from spreading or becoming depressed, also prevented from creeping, and stayed firmly at the joints.

Having thus fully described the invention, what is claimed as new is:—

1. A rail tie comprising a base plate having a vertical web provided with separated 45 portions at the ends thereof, and parts co-operating therewith and forming boxes or compartments and upper clamp supports on

the inner and outer sides thereof, rail supporting blocks disposed in said compartments, clamping devices engaging said clamp supports, and means for retaining said clamping devices in operative position.

2. A rail tie comprising a base plate having a vertical web, said web having spaced portions at each end of the tie, parts co-operating with said spaced portions to form an intervening box or compartment for the receipt of a rail supporting member, clamp supporting portions upon the spaced portions of the web on the inner and outer sides of the box, and rail clamps adapted to engage said clamp supporting portions.

3. A rail tie comprising a base plate having a vertical web, the web having spaced portions at each end of the tie, said spaced portions being provided at their upper edges with lateral flanges forming retaining seats, the outer seat being provided with a stop shoulder, transverse plates arranged to form with said spaced portions of the web an intervening box or compartment for the reception of a rail supporting block, clamps adapted to slidably engage the flanges of said seats, and means associated with the inner clamp for retaining the same in position.

4. A rail tie comprising a base plate having a vertical flange provided with spaced portions at each end, each of said spaced portions being provided with laterally extending flanges forming a supporting head or seat, transverse plates formed upon the base plate and web and connected at their ends and providing a box or compartment for the reception of a rail supporting block, rail clamping members slidably engaging the flanges of the supporting heads, and means associated with the inner clamping member for adjustably securing the same in position.

In testimony whereof I affix my signature 90 in presence of two witnesses.

JOHN M. FARRA.
